UNITED STATES PATENT OFFICE.

JONATHAN PETERSON, OF BROOKLYN, NEW YORK, ASSIGNOR TO COMBINATION
MACHINE COMPANY, A CORPORATION OF DELAWARE.

PLUG-TOBACCO.

1,217,496.

Specification of Letters Patent. Patented Feb. 27, 1917.

Application filed September 9, 1916. Serial No. 119,205.

To all whom it may concern:

Be it known that I, JONATHAN PETERSON, a citizen of the United States, residing at Brooklyn, in the county of Kings and State 5 of New York, have invented certain new and useful Improvements in Plug-Tobacco, of which the following is a specification.

This invention relates to manufactured tobacco products and has particular application to plug tobacco, such as may be used for chewing or smoking.

As is well known, plug tobacco is usually sold by the retail tobacco dealer to the consumer in small, homogeneous solidified 15 blocks or plugs which usually retail at five or ten cents each, for instance. In using such a homogeneous plug, it is the practice for the consumer to either cut off, or in many instances to bite off a portion sufficient to provide a chew or quid of the desired size or quantity. It often times happens that several persons will partake of the same plug of tobacco, which is obviously 20 unsanitary for many reasons, and in some instances may present the danger of serious infection to one or more of the users, especially where the practice of biting the plug is followed, or where the knife or other instrument employed in cutting off the small 25 piece or section is unclean, or perhaps carries an infecting germ. Furthermore, the cutting off of a section or piece to be chewed, or the biting thereof frequently requires such effort as to cause the breaking down 30 or shredding of the portions of the plug contiguous to the piece separated, with the result that when the plug is returned to the pocket of the person, shredded or disintegrated particles of tobacco are liable to fall 35 from the plug into the pocket, especially should such plug be partially dried out, as through atmospheric influence.

To obviate the above disadvantages, and others of a like nature which are well 45 known to consumers of plug tobacco, I have devised the present invention in the art of manufacturing and preparing plug tobacco for the ultimate consumer.

In the present instance I propose to pre- 50 liminarily and partially divide the pressed plug of tobacco into small sections or portions of a size suitable for chewing for instance, by cutting or incising such plug

from opposite sides or faces, a cut or incision in one side of the plug substantially 55 alining with but not meeting a cut or incision in the opposite side of such plug so that a web or unitary portion will extend throughout substantially the center or central plane of the plug, and the various sections formed by the incisions will be united by this web, so that each section or a multiple thereof, may be readily broken off to provide a chew or quid. Consequently the liability of a section or sections of the plug 60 being accidentally disconnected or broken off is obviated, while when the user desires to consume a piece of tobacco it is only necessary with the exercise of but very little force or effort to bend or break such piece 65 off from the remainder of the plug, the action of bending or breaking of course severing that portion of the web which unites the particular section to the plug.

Another object of the invention is to so 70 cut or incise the plug from opposite sides that in the act of breaking off a section the usual facing leaves or wrappers for the body of the plug will not be torn, split or broken from adjacent plug sections to such 75 an extent as to permit the filler of the plug 80 to disintegrate or shred away.

Furthermore, I propose to provide a plug 85 of tobacco of this character which will possess manifest features of advantage from a sanitary standpoint, inasmuch as it is unnecessary to employ an instrument such as a knife for cutting off a section of the plug, nor is it necessary to bite off a piece, as a section, or two or more sections, sufficient 90 to provide the desired chew or quid may be readily, conveniently and quickly separated from the remainder of the plug by the simple act of bending such section or sections relative to the plug body.

With the above recited objects and others of a similar nature my invention consists in the construction, combination and arrangement of parts set forth in and falling within the scope of the appended claims.

In the accompanying drawings,

Figure 1 is a perspective view of a plug of tobacco embodying my invention, with one of the sections thereof removed.

Fig. 2 is a cross sectional view taken 105 through the plug shown in Fig. 1 and illus-

trating the manner in which the incisions are formed so as to leave a uniting web in the central plane or portion of the plug.

Fig. 3 is a detail view of the portion of the plug showing more clearly the manner of separating a section therefrom.

Referring now to the accompanying drawings in detail, the letter A indicates as an entirety an ordinary pressed plug of tobacco which may be of any shape or form and has the opposite sides 1 and 2 thereof provided with the usual wrapper or facing sheets 3 of leaf tobacco. In producing the form of plug shown herein, I subdivide such plug into small squares or sections 4 of suitable size for chewing by the spaced parallel cuts or incisions 5 and the spaced parallel cuts or incisions 6, which cross the rows of cuts or incisions 5 at right angles, as clearly shown in Fig. 1. The plug is cut or incised in this manner at both of the sides 1 and 2, the cuts 5 at one side of the plug alining with the cuts 5 of the opposite side thereof, while similarly the cuts 6 at opposite sides of the plug are also in alinement. However, these cuts or incisions 5 and 6 are relatively shallow, that is to say, are not made deep enough for oppositely disposed alining cuts to meet at the center of the plug, and therefore a web or connecting strata 7 of the tobacco extends throughout the central portion or plane of the plug and unites the various squares or sections. Thus, such squares or sections of tobacco will remain united by the web until sufficient force or effort is applied to break off a desired section or sections, as shown in Fig. 1. Such section or sections may, however, be readily detached from the remainder of the plug by a slight effort exerted in bending the desired piece back and forth as indicated in the full and dotted lines in Fig. 3. This bending action will, of course, result in the rupturing of the web section which connects the particular plug section to the main portion of the latter. However, it will be seen that as the wrapper leaves covering opposite faces or sides of the plug are severed or sub-divided by the cuts or incisions 5 and 6, the act of detaching a section will not result in the tearing or breaking of the contiguous portions of the wrapper leaves, as is likely to result in separating a piece from the ordinary plug of tobacco.

Furthermore, it will be noted that with the present form of plug the oppositely disposed cuts or incisions are, as before stated, relatively shallow, which is an advantage 60 from the manufacturer's standpoint in preparing the present plug for the market, inasmuch as the necessity of making relatively deep cuts in one side or face of the plug is avoided, and this, of course, obviates the liability of cutting entirely through the

plug, or so deep as to result in the accidental separation of the various plug sections. In other words, in making the cuts or incisions in one side of the plug only, it is difficult to accurately gage the depth of such cuts, 70 that is to say, to make the cuts deep enough without entirely cutting through the plug or completely separating the latter into sections. With my arrangement, however, as the plug is cut from both sides, the incisions 75 are so shallow as to render it an easy matter to accurately gage the depth of cut desired.

It will further be noted that the intersecting cuts or incisions at the opposite sides 80 of the plug do not cause the removal of any substantial portion of the tobacco at the points where the cuts are made, which would be the case were grooves or the like formed in the faces of the plug, but on the contrary 85 these cuts are so narrow or thin and sharply defined that the homogeneous nature of the plug is not substantially changed, and therefore no deep grooves or indentations are formed, which would result in hastening the 90 undesired drying out of the plug.

While I have herein shown and described a plug of tobacco of a particular shape having the cuts or incisions thereof arranged in a particular formation, I wish it to be 95 understood that I do not limit myself to such details, as modifications and variation may be made in such respect without departing from the spirit of the invention or exceeding the scope of the appended claims. 100

What I claim is:

1. A plug of tobacco having spaced cuts in opposite sides thereof partially sub-dividing said plug into a series of sections, said cuts leaving web sections at substantially 105 the central portion of the plug, so that each section, or multiple thereof, may be readily broken off to provide a chew or quid.

2. A plug of tobacco having spaced cuts in opposite sides thereof partially sub-dividing said plug into a series of sections, the cuts at one side of the plug substantially alining with corresponding cuts at the opposite side thereof, said alining cuts leaving web sections at substantially the center 115 of the plug, and which web sections unite the plug sections for ready separation, so that each section, or a multiple thereof, may be readily broken off to provide a chew or quid.

3. A plug of tobacco having spaced intersecting cuts in opposite sides thereof partially sub-dividing said plug into a series of sections, the intersecting cuts in one side of the plug substantially alining with the 125 corresponding intersecting cuts in the opposite side of the plug whereby web sections are formed at substantially the center of the plug, and which web sections unite the plug sections for ready separation, so that 130

each section, or a multiple thereof, may be readily broken off to provide a chew or quid.

4. As a new article of manufacture, a plug of tobacco composed of a plurality of unit sections partially disconnected from one another by lines of separation extending inward from opposite faces of the plug, said sections being integrally united by a relatively thin connecting web of the tobacco 10 located in substantially the central plane of

the plug, each of said sections or a multiple thereof constituting a quid or chew and being readily separable from one another.

In testimony whereof I affix my signature in the presence of two witnesses.

JONATHAN PETERSON.
